CRIB FOR BABIES

Lydia Adolfina Hagelfeldt, Stockholm, Sweden,
assignor of one-third to George Blomquist, New
York, N.Y.

Application July 3, 1948, Serial No. 36,943

5 Claims. (Cl. 5—98)

1

This invention relates to beds for babies and infants of the type known as cribs.

One of the objects of the invention is to provide a novel and improved crib of the general type, above referred to, which can be conveniently and rapidly set up and collapsed or folded without requiring the use of tools or mechanical skill.

Another object of the invention is to provide a novel and improved crib of the general type, above referred to, which is comfortable and safe in use and so light in weight that it can be carried or moved from one place to another, either folded or set up, without appreciable effort.

Another object of the invention is to provide a novel and improved crib of the general type, above referred to, which, when folded, forms a comparatively small and compact package that may be carried in a suitable bag or trunk.

Another object of the invention is to provide a novel and improved crib of the general type, above referred to, in which the side walls are detachably secured to the crib proper, thereby permitting convenient use of the crib as a dressing table after removal of the side walls.

Another object of the invention is to provide a novel and improved crib of the general type, above referred to, to which either side walls of comparatively strong solid material or a hood structure closed at the top and made of a material such as mosquito netting can be selectively and detachably secured. This arrangement has the advantage that, whenever circumstances make it desirable, the solid side walls made of material such as canvas or duck can be replaced by the walls made of netting material thereby permitting free access of light and air while protecting a baby against falling out of the crib.

Another object of the invention is to provide a support cover for a crib of the general type, above referred to, which can be conveniently and simply removed from the frame structure of the crib for purpose of cleaning or replacing the cover.

Another object of the invention is to provide an adjustable safety belt fastened to the frame structure of the crib, thereby further protecting a baby placed in the crib.

Other and further objects, features and advantages of the invention will be pointed out herein-after and set forth in the appended claims forming part of the application.

In the accompanying drawing a now preferred embodiment of the invention is shown by way of illustration and not by way of limitation.

2

In the drawing:

Fig. 1 is a perspective view of a crib according to the invention set up with solid side walls.

Fig. 2 is a perspective view of a crib according to the invention set up with a hood made of netting material.

Fig. 3 is a perspective view of the frame structure of the crib in unfolded position.

Fig. 4 shows the frame structure in substantially folded position.

Fig. 5 is a side view of the pivot and locking means for one of the legs of the crib on an enlarged scale.

Fig. 6 is a section along line 6—6 of Fig. 5.

Fig. 7 is a bottom view of Fig. 1.

Fig. 8 is a bottom view similar to Fig. 7 after removal of the side walls, and

Fig. 9 is a top view of the crib without side walls.

Referring now to the figures in detail, the crib as shown on the drawing comprises a substantially rectangular frame, generally designated by 10, made of any suitable material such as metal tubes. The frame is composed of two equal frame portions 11 and 12 joined by hinges, generally designated by 13. Each hinge comprises two brackets 14 and 15 pivotally connected by a pin 16. As will be noted, the hinge brackets extend downwardly from frame 10 when the crib is set up.

Frame 10 is supported by four legs 17, 18, 19 and 20 joined by cross bars 21 and 22 respectively. Each leg is pivoted to the frame, as can best be seen on Figs. 5 and 6. An arm 23 having an eyelet extends from each corner of the frame and is engaged between the two arms of a fork 24 provided at the end of each leg. A pivot pin 25 serves to pivot the legs to the frame proper. Each leg is further provided with a lateral extension 26 having an opening 27 therein. Each extension 26 is so shaped that it will abut against the frame when the legs are unfolded for supporting the frame, as can best be seen in Figs. 3 and 5. For the purpose of locking the legs in their supporting positions, eyelets or holes 28 are provided in the four corners of frame 10 so positioned that respective holes 27 and 28 are in alignment when the legs are in the positions shown in Fig. 3 and 5. It will be evident that a bar 29 extending through holes 27 and 28 will lock the legs in their supporting positions thereby preventing an accidental collapse of the crib.

For support of a mattress as conventionally used in cribs of the type herein referred to, a support cover 30 is provided preferably made of

suitable fabric such as canvas or duck. This cover has a substantially rectangular shape corresponding to the rectangular frame 10 and can be fastened to the frame proper by any suitable means such as comparatively narrow tongues 31 provided spaced apart along the long sides of the cover and comparatively wide tongues 32 on the short side of the cover. These tongues are folded over the tubes of the frame and secured by means of strings or cords 33 threaded through eyelets 34 in the tongues and eyelets 35 provided in the cover directly or in fabric straps 36 sewed or otherwise secured to the cover. As can best be seen in Figs. 7 to 9, a gap is left for hinges 13 between two cover tongues which gap is also free of string portions so that the frame can be folded without difficulty. To secure the cover part adjacent to the hinges when the frame is set up, two straps 37 are provided, each having a slot 38 which can be slipped over the downwardly extended brackets 14, 15 of the hinges and is removed from the hinges (see Fig. 9) preparatory to the folding of the crib frame.

As will be apparent, the support cover remains normally secured to the frame but can be conveniently removed for purpose of cleaning or replacement when worn.

A conventional mattress (not shown) may be placed upon the support cover. However, the crib can also be used as a dressing table in which case the mattress and the side walls (more fully described hereinafter) will not be used.

As previously mentioned, a crib according to the invention may be used either with solid side walls open at the top or with side walls made of netting material and closed at the top.

According to Fig. 1, side walls 40 are shown as comprising one or several strips of sufficiently strong solid fabric so sewed or otherwise secured together that the strips may be unfolded or stretched to form a rectangle confining substantially the same area as the frame. The side walls thus formed are stiffened and detachably secured to the frame by means of a plurality of substantially rigid bars 29 and 29'. These bars may be permanently or removably secured to the fabric of the side walls, for instance by means of pockets 41, loops, eyelets or any other suitable means as known for such purposes in the art. For purpose of securing the bars to the frame, a corresponding number of holes 28' in addition to the corner holes 23 are provided. When it is desired to secure side walls 40 to the frame, the ends of bars 29 and 29' are inserted into the corresponding holes of the frame as can best be seen in Fig. 1. It will be apparent that corner bars 29 serve a dual purpose, namely as stiffeners for the side walls and as locks for the legs.

To further secure the side walls to the frame and also to close all gaps along the lower edges of the side walls, the latter are provided with extensions 42 and 43 respectively extending from the short sides and the long sides of the side walls. These extensions may be turned over the frame and slipped by means of eyelets 44 over the protruding ends of the bars as can best be seen on Fig. 7. This figure also shows that the side walls are secured along practically their entire lower edge to the frame. Slots 43' permit the middle part of extensions 43 to be slipped over the hinges 13 thereby further securing the side walls.

When it is desired to fold the crib, the side walls are first removed by slipping the eyelets 44 in the extensions 42 and 43 off the ends of

the bars whereupon the entire side walls may be conveniently pulled off. The side walls can now be rolled or folded together, removal of the bars from the side walls being not necessary. The removal of the bars from the frame also unlocks the legs so that the frame can be folded into the position shown in Fig. 4.

While Fig. 4 shows a frame without support cover and mattress, it should be understood that it is by no means necessary to remove the cover for folding the crib and that the mattress may be folded over the frame so that a comparatively small and compact package is formed which can be carried in a suitable bag or trunk. The bag or trunk is preferably so dimensioned that the different side walls used in connection with the crib, blankets, sheets and all other items useful or necessary in the care of a baby can be placed in the same bag or trunk.

According to Fig. 2, the side walls are shown as comprising a hood like structure 45 made of a light fabric such as mosquito netting and closed at the top. The hood is stiffened by a pair of substantially U-shaped bars 46 and 47 which are inserted into corner holes 28 of the frame and hence also serve as locks for the legs. As the bars are U-shaped, it is generally not necessary to secure the same to the netting material although this may be advantageous in certain instances. If found to be necessary or desirable, more than two bars may be provided which are then inserted into holes 28. It is further possible to use single bars such as shown in Fig. 1 although U-shaped bars are generally preferable. The lower edges of the side walls of hood 45 are preferably secured to the frame by means of extensions of has been described in connection with Fig. 1.

The main purpose of using the hood according to Fig. 2 is to afford full access of air and light to a child placed in the crib while fully protecting the child against falling out of the crib and also against flies and other insects.

To guard a child against glare or draft, part of the hood may be covered with or replaced by a substantially solid material 48.

A baby placed in the crib may be further protected by means of an adjustable safety belt, generally designated by 50. This belt comprises two straps 51 and 52 fastened at opposite edges of cover 30 to permit placement of a mattress between the straps. Fastened to strap 52 is a third strap 53 forming a loop with strap 52. Strap 53 may be buttoned to strap 52. Several button holes 54 are preferably provided to adjust the width of the loop. A buckle 55 serves to join straps 51 and 52 after the loop is slipped over the baby.

What is claimed as new and desired to be secured by Letters Patent is:

1. A crib comprising a substantially rectangular frame for supporting a mattress, said frame being composed of two symmetrical substantially U-shaped rigid frame portions, four legs pivoted each at one end thereof adjacent one of the four corners of said frame, a plurality of substantially rigid bars, each of said legs having a lateral extension at said one end positioned to abut against the frame when the legs are pivoted into positions for supporting the frame, said extensions having each an opening therein, said frame having openings therein positioned to be in alignment with the extension openings when the legs are in the frame supporting positions, each extension opening and the corresponding frame

opening being arranged to receive slidably one of said bars for detachably locking the legs in said frame supporting positions, and a pair of hinge means joining the two symmetrical frame portions and folding the same about a transverse axis, each hinge means being formed from a pair of brackets connected to the adjacent ends of the corresponding sides of the rigid frame portions and extending from said ends transversely to the axes of said sides, the adjacent ends of the brackets of each hinge means being pivoted together, the said brackets abutting one against the other when the two frame portions are in aligned position thereby holding the frame in the said position, and being substantially in alignment when the frame is folded about said transverse axis, thereby providing space for the legs between the folded frame portions.

2. A crib as defined in claim 1, wherein each of said side branches of the two frame portions has intermediate transverse openings therethrough, each of said openings being adapted to receive one of said rigid bars for providing support to the side walls of the crib.

3. A crib as defined in claim 1, wherein the rigid bars for insertion into the four openings of the frame comprise a pair of U-shaped bars, the side branches of each of said U-shaped bars being spaced to fit into two openings of the frame.

4. A crib as defined in claim 1, in combination with pliable side walls for the crib in the form of a substantially rectangular body corresponding in outline to the rectangle defined by the frame when the said rigid frame portions are in aligned position and being adapted to be fitted

upon the frame in a position in which each of said bars forms an inner corner post for the side walls when the said bars are fitted in the leg and frame openings thereby stiffening the said side walls.

5. A crib as defined in claim 4 wherein the said side walls are made of netting material and are continued in a top wall also made of netting material, and wherein a cover made of pliable substantially opaque material is fitted upon a portion of the top wall and portions of the long side walls adjacent to the short side walls of the side wall body so as to form a protective shield against light and draft for a child placed in the crib.
